(57) **CLAIM**

The ornamental design for “winding visor”, as shown and described.

DESCRIPTION

FIG. 1 is a perspective view of “winding visor” showing my new design

FIG. 2 is a top plan view of FIG. 1;

FIG. 3 is a front elevational view of FIG. 1;

FIG. 4 is a right side elevational view of FIG. 1: the left side is a mirror image.

FIG. 5 is a right side elevational view of FIG. 1 showing shape of my new design when worn.

FIG. 6 is a rear view of FIG. 1; and,

FIG. 7 is a bottom plan view of FIG. 1.

The broken lines shown on the winding visor represent stitching.
